UNITED STATES PATENT OFFICE.

WILLIAM J. MURDOCK, OF CHELSEA, MASSACHUSETTS.

COMBINED KNOB AND DIAL.

Application filed July 29, 1922. Serial No. 578,309.

To all whom it may concern:

Be it known that I, WILLIAM J. MURDOCK, a citizen of the United States, residing at Chelsea, in the county of Suffolk and State 5 of Massachusetts, have invented new and useful Improvements in Combined Knobs and Dials, of which the following is a specification.

The present invention is concerned with 10 a combined article which is at the same time a knob adapted to be applied to a shaft and by which the shaft may be rotated, and a dial for measuring with respect to a scale of angular degrees or other graduations the 15 amount of rotary movement thus given to the shaft. The purpose of the invention is to provide a device of this nature having improved means for detachably and adjustably securing it to the shaft on which 20 it is applied. For a statement of the exact nature of the improvements in which the invention consists, attention is directed to the following specification containing a description in detail of the preferred embodiment of the invention, and to the drawings 25 referred to in such specification.

In the drawings,—

Figure 1 is a perspective view showing the improved device and its mode of use.

Figure 2 is an axial section of the same.

Figure 3 is an elevation, detached from its surroundings, of the bushing which is a part of the combined knob and dial.

The combined knob and dial with which 35 this invention is concerned is adapted to be applied in front of or over a panel, on the end of a shaft which projects through such panel. Different conditions under which a knob of the same design is to be used require 40 that the manner of its attachment to the shaft be adjustable, since different thicknesses of panel or different lengths of shaft may cause the protruding shaft end on which the knob is to be applied to project 45 more or less far from the panel, while practical conditions require that the dial be placed to the panel.

The combined knob and dial which, for brevity, I will generally refer to simply as 50 a knob, consists of a head *a* with which is connected a skirt or flange *b* having a beveled surface *c* bearing graduation or scale marks *d*. This knob is required to be applied to a shaft *e* which protrudes at one 55 end from a panel *f*.

Conveniently the entire knob is molded

as an integral unit from a plastic composition, as vulcanite, and in order to give strength and wearing quality to that part which receives the shaft there is embedded 60 in the mass of the material, while plastic, a bushing *g* having a groove *h* to receive the plastic material so as to prevent its withdrawal, and a knurled or otherwise roughened surface *i* to prevent the knob from 65 turning upon it.

The bushing is adapted to be slipped over the shaft end, and to secure it on the shaft there is provided a set-screw *j* which is threaded through the side of the bushing so 70 as to bear against the shaft and has a long shank passing through a groove or passage in the skirt *b* to an orifice *k* in the beveled face thereof. Thus the head of the screw 75 is readily accessible.

The location of the set-screw in the position shown, brings it close to that end of the knob which is contiguous to the panel, or in other words, remote from that end of the knob toward which the protruding shaft 80 projects. This is important because it affords the greatest possible range of adjustment of the knob, allowing it to be attached to a shaft having only a minimum extent of protrusion from the panel. Another advantage resulting from this location, in comparison with a possible location of the screw 85 in the head *a*, is that its presence does not cause any projection or other breaking of continuity in the sides of the knob which 90 have to be engaged by the fingers of the operator, thus increasing the comfort of the operator in handling the knob.

Various modifications may be made in the 95 structure of the knob and dial combined within the scope of the invention and of the protection which I claim. Thus, for instance, instead of making the combined article as an integral structure, the different elements may be separately made and connected together, whereby the finished article 100 is a unit structure, as well as when they are integrally united together. In the case last indicated the skirt or flange may be made of sheet metal, or other sheet material, suitably formed to provide the peripheral surface which bears the indicating graduations, or of cast metal or other cast or molded plastic material, and attached by suitable fastening means to the head. However 105 made, the skirt or flange provides an interior space back of its outer surface in which

the set-screw is contained and concealed, and an orifice in its peripheral face or surface through which the head of the set-screw is accessible for setting up or loosening.

5 What I claim and desire to secure by Letters Patent is:

1. A combined knob and dial formed as a unit structure adapted to be applied on a shaft, a bushing in said structure, and a set-screw threaded in said bushing and being accessible for adjustment through the peripheral face of said dial.
- 10

2. A combined knob and dial comprising a knob proper and a flange united as a unit structure, said flange having a beveled or peripheral surface provided with index marks, a bushing embedded coaxially in said structure, and a set-screw threaded into the side of said bushing and contained within said flange, with its outer end accessible 20 through the beveled face of the flange.

In testimony whereof I have affixed my signature.

WILLIAM J. MURDOCK.
